MANUFACTURE OF SHOULDER PADS

Katherine Kerrigan, Waverly, N. Y.

Application April 11, 1946, Serial No. 661,222

3 Claims. (Cl. 2-268)

1

This invention relates to manufacture of shoulder pads; and it comprises a shoulder pad of concavo-convex form having a point at one end with substantially straight sides merging into a rounded base and adapted to rest on the shoulder with the tip of the shoulder in the concavity of the pad and the point of the pad directed towards the base of the neck. The invention also includes a method of making the described pad; all as more fully hereinafter set forth and as claimed.

Shoulder pads have, of course, been used for many years and many different types and forms have been proposed. Most of these prior art shoulder pads have been adapted for men's clothing and few have been capable of use in ladies' wear. Men's and ladies' shoulder pads have distinctively different requirements. For example, ladies' shoulder pads, which are adapted to be used in shirt waists, dresses, sweaters and the like, should be readily detachable from the garments so that the latter can be washed or cleaned. While a few ladies' shoulder pads have been described which are provided with detachable features, such as snap fasteners, these have been troublesome to operate and cumbersome.

I have developed a shoulder pad especially adapted for use in connection with ladies' garments which tends to stay in place without slipping to such an extent that it normally requires no direct attachment to the garment with which it is worn. This pad is of concavo-convex form having a point at one end and a smoothly rounded base at the other and it is adapted to rest on

2

the shoulder with the top of the shoulder in the concavity of the pad and with the point of the pad directed towards the base of the neck. I have found that, if the top of this pad is constructed of some type of non-skid material, such as cotton or rayon net jersey, doe skin, cotton wadding, sponge rubber or the like, the friction against the garment is sufficient to retain the pad in position. It is usually desirable to provide means for securing the pad to a shoulder strap, for example, but the pad need not be attached or secured to the garment which it serves to pad. This enables the garment to be removed or changed without removal of the shoulder pad which, of course, is a distinct advantage. The garments themselves do not require separate padding. A single pair of pads can therefore do for several garments. In addition I have found an advantageous method of making the described pads.

My invention can be explained more accurately by reference to the accompanying drawing which shows, more or less diagrammatically, several views of my shoulder pad. In this showing,

Fig. 1 is a plan view of a pattern used in cutting out the materials used in making one section of my pad.

Fig. 2 is a plan view of a second pattern used in cutting out the materials for the other section of the pad.

Fig. 3 is a plan view of a pattern used in cutting out padding or filling material used in making the pad.

Fig. 4 is a plan view of another pattern used in cutting out filling material for the pad.

Fig. 5 is a plan view of the completed pad.

Fig. 6 is a cross section through the center of the pad, taken along the line 6-6 of Fig. 5, while

Fig. 7 is a similar cross section of a modified pad formed of a molded plastic material.

In the various figures like parts are designated by like reference numerals. My completed pad, as shown in Fig. 5, in plan view, has a point 1 at one end and an arcuate base 2 at the other end. The rounded base is substantially circular in outline, while the point is made by two substantially straight edges which intersect at an angle of about $90^\circ \pm 25^\circ$, these edges being approximately tangential to the circular base. The pad is convex on the top with the maximum convexity occurring close to the base, as shown in cross section in Fig. 6. It is concave from below with a shape which closely fits the tip of the shoulder. The point of maximum thickness occurs at approximately the point of maximum

convexity, so that the under side has less curvature than the top.

As shown in Fig. 6 I usually make my pad with up to 6 plies of material. A ply of cotton wadding or equivalent is shown on the top and bottom at 5 3 and 4, respectively. Two plies 5 and 6 of unbleached muslin or equivalent material having a desired stiffness are placed beneath the top ply. And between these plies and the bottom ply there are two thicker layers 7 and 7a of filling material, such as cotton batting. The upper filling ply is smaller than the lower which is centered approximately at the point of greatest convexity.

The pad of Fig. 5 is made by using the patterns shown in Figs. 1 and 2 for cutting out the top and bottom plies and the plies of unbleached muslin, and the patterns shown in Figs. 3 and 4 for cutting out the filling material used in making plies 7 and 7a, respectively. It will be noted that the pattern of Fig. 1 is substantially diamond shape except that the base lines are slightly convex and the bottom point is rounded. The pattern of Fig. 2 has a shape substantially that of a new moon. The point 1a at the top of the pattern of Fig. 1 forms the point 1 of the finished shoulder pad, while the base 2a of the pattern of Fig. 2 forms the base 2 of the finished pad.

In making the pad two layers of unbleached muslin are first placed between two layers of cotton wadding, then this assembly is cut with dies into two blanks using the two patterns of Figs. 1 and 2. One of the outer layers of cotton wadding is removed from the resulting blanks, to be used in making the bottom ply of the pad. The three remaining plies of the two blanks, corresponding in shape to the two patterns, are then machine stitched together in such fashion that the points 8, 9 and 10 coincide with points 8a, 9a and 10a, respectively. The seam should be about $\frac{1}{4}$ inch in width and should fall on the unbleached muslin side. Owing to the difference in curvature between the two patterns a uniform cupping of the material is produced, as indicated in Fig. 6. The resulting combined blank is then shaped by pressing on a form using a damp cloth, with the muslin layers inside, the blank assuming the form shown in Figs. 5 and 6. A blank is then cut from cotton batting with a thickness of $\frac{1}{2}$ inch, using the pattern of Fig. 3 and another blank from a $\frac{3}{4}$ inch thickness of cotton batting, using the pattern of Fig. 4. The latter blank is centered on the former and the edges of both are frayed so they taper to a thin edge all around, after which the assembly is pressed on a form with a damp cloth to form a filling blank corresponding to plies 7 and 7a of Fig. 6. This filling blank is then united with the combined blank produced previously. This can be accomplished by coating the inside muslin surface of the combined pad with glue over the shaded area designated A in Fig. 5. Any type of lacquer or glue can be used for this purpose. A nitrocellulose or casein cement has been found very satisfactory. The filling blank is then pressed against the freshly glued surface and pressure is applied, with heating if necessary. The two filling layers cover approximately the shaded areas indicated at A and B in Fig. 5. The resulting blank or shell is now ready for application of the bottom lining of cotton batting.

The bottom lining is produced from the cotton wadding blanks removed from the first assemblies which were cut over the patterns of Figs. 1 and 2. These two blanks are first sewed together along 8—9—10 and 8a—9a—10a and the resulting shell

is pressed on a form with a damp cloth with the seam on its convex side. The resulting formed shell is then fitted inside the other and the shells are united by stitching approximately along the dotted line designated C in Fig. 5, after which the edges of the inner shell are trimmed away and the assembled pad is pressed on a form once more, making the completed pad. The edges can be pinked if desired.

The above pad can usually be employed without any means for securing it to the clothing. It is usually desirable, however, to provide means for attaching it to a shoulder strap. In this case a tape 11 is provided, this being sewed on the top 15 of the pad at a distance of about 2 inches from the tip, as shown in Figs. 5 and 6. A snap fastener 12 is advantageously provided so that the tape can be snapped on over the shoulder strap.

The pad shown in section in Fig. 7 is formed from a resilient plastic, such as sponge rubber. This is molded to proper shape in a mold and requires no sewing or other operations although, of course, it may be encased in a fabric, if de- 20 sired.

It will be noted that the concave portion of the base of my shoulder pad is intended to fit over the tip of the shoulder, the point 1 of the pad pointing towards the neck. It fits the shoulder so well that there is little if any tendency for the 25 pad to slip out of position. The fastening strap 11 is convenient, however, to prevent the pad from falling off the shoulder when the garment to be padded is being put on or taken off. After the garment is on, the friction between the anti-skid upper surface of the pad and the garment is sufficient to retain it in proper position. It is thus evident that no means is required for attaching the pad to the garment to be padded.

While I have described what I consider to be 30 the best embodiments of my shoulder pads, it is evident of course that many modifications can be made in the selection of materials, in the methods of making and in the structures of my pads without departing from the purview of this invention.

While I have described pads made of several plies 45 of fabric materials and pads made of molded sponge rubber or other resilient plastic, it is also possible to combine plies of fabric with plies of plastic materials. My pads may be made without

any special casing or covering material or, on 50 the other hand, in the more expensive models the pads may be encased in glove silk, flannel, rayon or the like. As indicated previously, however, I prefer to have the top of my pad of some

type of non-skid material, such as chamoisette, 55 cotton wadding, jersey, mole cloth, foam rubber, felt, flannelette, knitted wide wale cotton cloth, crepe fabrics, piled fabrics and the like, hence if a casing is used, it is advantageous to make it

out of such a material, at least on top. At the 60 same time it is advantageous to make the casing, as well as the pad as a whole, of as light weight materials as possible. Any suitable filling mate-

rials can be used, including cotton batting, kapok, 65 wool felt, sponge rubber, jute etc. Any suitable stiffening material can be employed, such as crinoline, buckram, tarlatan, muslin and the like. Or if desired, a stiffening ply can be made by coating fabric with a cellulose varnish, lacquer

or the like. It is possible to make the pad with 70 a single ply of felt or equivalent which is cut or formed into the required shape, this ply being advantageously encased in some type of fabric. A felt pad requires no special stiffening. The two 75 blanks used in making the shells of my pad can be

combined by cementing the blanks together at their edges, if desired, but it is easier to sew them together. And it is, of course, possible to sew the filling material into the top shell rather than gluing it in position as described above. Casein cement can be used to hold the plies together.

The edges of the point of my pads can be made substantially straight, as in Fig. 5, or somewhat convex. The amount of filling material used can be varied widely in order to produce pads of different height and thickness. And, of course, the pads can be varied in size. In fact it is convenient to supply the pads to the trade in different sizes and with varying heights. Other modifications of my invention which fall within the scope of the following claims will be immediately evident to those skilled in this art.

What I claim is:

1. A shoulder pad of concavo-convex form having a rounded base at one end and a point at the other with sides which merge into the base, adapted to fit with the tip of the shoulder in the concavity of the pad and the point of the pad directed towards the base of the neck, said pad having a top-surface of non-skid material and comprising a plurality of laminations at least one of which is of stiffening material and another of filling material, and means secured to the top-surface of the pad for removably attaching the same to a shoulder strap, said pad being adapted to be held on the shoulder solely by its non-skid top-surface, by its concavity and its attachment to said shoulder strap.

2. In the manufacture of shoulder pads the process which comprises cutting two blanks from fabric material substantially in the form of diamonds but having one point rounded slightly, cutting two other blanks substantially in the form of new moons, sewing the blanks together in pairs with said rounded points in the centers of the concavities of the moon-shaped blanks, thereby forming two cup shaped shells, affixing a filling material in the concavity of one of said shells to produce thickness, attaching the other shell to the concave side of the filled shell over the filling

5 material, to form a pad having a concavity adapted to fit the tip of the shoulder, and securing a tape adapted to removably engage a shoulder strap to the convex surface of the so-formed pad.

3. A shoulder pad comprising two blanks of fibrous materials one substantially in the shape of a new moon and the other in the shape of a diamond with one point rounded, said blanks being combined with the rounded point of the diamond-shaped blank in the center of the concavity of the moon-shaped blank and with adjacent points and edges of both blanks joined to produce a concavo-convex form with a smoothly rounded convexity close to a rounded base at one end and a point at the other end, a fastening tape mounted on top of the pad permanently secured at one end and provided at the other end with a detachable fastener, said tape being adapted to 10 removably engage a shoulder strap passing over the top of the pad, said pad being adapted to rest on the shoulder of the wearer with the tip of the shoulder in the concavity of the pad and the point of the pad directed towards the base of 15 the neck, said pad being free from attachment to the garment which it serves to pad, having a top surface of non-skid material and being adapted to be held on the shoulder solely by its concavity, its non-skid surface and its attachment to said 20 shoulder strap.
